UNITED STATES PATENT OFFICE.

STANDLEY D. GROMER, OF TUCSON, ARIZONA.

BATHING APPARATUS.

1,359,985.

Specification of Letters Patent. Patented Nov. 23, 1920.

Application filed March 8, 1920. Serial No. 363,982.

To all whom it may concern:

Be it known that I, STANDLEY D. GROMER, a citizen of the United States, residing at Tucson, in the county of Pima and State of Arizona, have invented a certain new and useful Improvement in Bathing Apparatus, of which the following is a full, clear, and exact description, reference being had to the accompanying drawings.

10 This invention relates to bathing apparatus and has for its objects to provide an apparatus of this character which shall consist of few and simple parts that may be easily and quickly folded to a compact package and hence rendered portable; to provide a bathing apparatus which shall be interchangeable with the city water mains and with a container for use where water under pressure is unavailable; to provide an apparatus which shall deliver water in variable quantities under the control of the operator to the parts being bathed; while further objects and advantages will appear as the description proceeds.

15 In the accompanying drawings wherein I have shown an illustrative embodiment of my invention; but without intent to limit myself thereto, Figure 1 is a view showing my apparatus in operative position and 20 ready for use by the bather; Fig. 2 is a similar view showing my apparatus applied to the city water mains; Fig. 3 is a longitudinal sectional view of one of the bathing mittens; and Fig. 4 is a vertical sectional view thereof.

25 Describing the various parts by reference numerals, 1 indicates the main supply tube, consisting preferably of a rubber hose which may be connected at one end to any source 30 of water, such as a container 2 which may be of the collapsible or rigid type or may be connected to the house water mains as indicated at 3. The other end of the hose 1 is connected to a T or Y connection 4 which 35 diverts the water into each branch 5. The branches 5—5 may also be made of rubber hose and each projects into a bathing mitten 6, between the thumb and forefinger thereof

as illustrated in Figs. 3 and 4. The mittens 6 may be made of any porous material such 50 as rough Turkish toweling or other suitable material, and each is preferably provided with an elastic wrist band 7 to firmly engage the wrist and prevent the mitten from working loose during the bathing operation.

55 The supply of water to the mitten is controlled in the main supply hose by a snap clamp 8 positioned thereon, and also in each of the branches 5 by pressure of the thumb 60 and index finger or end of the hose inside of each mitten.

65 While I have described my apparatus as used in connection with water for ordinary bathing purposes, it will be understood that it is not limited thereto and may also be used for other purposes, such as applying a medicated solution to a specific part of the anatomy.

Having thus described my invention, what 70 I claim is:—

75 1. A device of the class described comprising a main supply line adapted to be connected to a source of liquid, a plurality of branches extending therefrom the end portion of each of said branches being extended into a hollow porous hand covering at a point adjacent the operator's fingers whereby the supply of liquid thereto may be controlled by pressure of the fingers on 80 said extension.

85 2. A device of the class described comprising a main supply line adapted to be connected to a source of liquid, means for controlling the supply of liquid in said line, 90 a pair of branches connected to said supply line and extending each into a hollow porous mitten between the thumb and forefinger thereof, said extension being of such length as to permit pressure thereon to control the supply of liquid independently in each mitten.

95 In testimony whereof, I hereunto affix my signature.

STANDLEY D. GROMER.
